(74) Attorney, Agent, or Firm — Hanley, Flight and Zimmerman, LLC

(57) **CLAIM**

The ornamental design for an “acoustic imaging device”, as shown and described.

DESCRIPTION

FIG. 1 is a right, front perspective view of an acoustic imaging device having rectangular apertures for microphones.

FIG. 2 is a front view of the acoustic imaging device of FIG. 1.

FIG. 3 is a rear view of the acoustic imaging device of FIG. 1.

FIG. 4 is a top view of the acoustic imaging device of FIG. 1.

FIG. 5 is a bottom view of the acoustic imaging device of FIG. 1.

FIG. 6 is a right side view of the acoustic imaging device of FIG. 1; and,

FIG. 7 is a left side view of the acoustic imaging device of FIG. 1.

The broken lines show portions of the acoustic imaging device that form no part of the claimed design; the broken lines and unshaded surfaces form no part of the claimed design.

1 Claim, 5 Drawing Sheets(56)
